TREE-SIMULATING CHRISTMAS CARD HOLDER

Mary Z. Hovlid, 5271 E. Anaheim Road,
Long Beach, Calif.

Filed Apr. 22, 1957, Ser. No. 654,332

2 Claims. (Cl. 40—124)

The present invention relates generally to the field of greeting cards and more particularly to a holder for displaying greeting cards.

It is a major object of the present invention to provide a novel and improved holder for displaying Christmas cards.

The card holder of the present invention fulfills the need for a device which will permit the large number of Christmas cards received each holiday season to be displayed in the home. This card holder may also be substituted for the conventional Christmas tree as an ornamental display when a plurality of Christmas cards have been attached thereto so as to add to the holiday enjoyment.

Another object of the invention is to provide a tree-simulating Christmas card holder which may be readily assembled and disassembled. Accordingly, the holder may be stored between Christmas seasons in a comparatively small space. Additionally, it may be shipped and merchandised in a comparatively small package.

Yet another object of the invention is to provide a tree-simulating Christmas card holder which is simple of design and rugged of construction whereby it may be utilized several seasons before requiring replacement.

An additional object is to provide a tree-simulating Christmas card holder which is inexpensive to manufacture.

These and other objects and advantages of the present invention will become apparent from the following detailed description, when taken in conjunction with the appended drawings wherein:

Figure 1 is a perspective view of a preferred form of tree-simulating Christmas card holder embodying the present invention;

Figure 2 is an enlarged horizontal sectional view taken on line 2—2 of Figure 1;

Figure 3 is an enlarged perspective view of a branch-simulating element of said holder; and

Figure 4 is a fragmentary perspective view showing how said branch-simulating element is affixed to the trunk-simulating element of said holder.

Referring to the drawings, the preferred form of tree-simulating Christmas card holder embodying the present invention includes an upright trunk-simulating post P, a base F secured to the lower portion of this post and a plurality of branch-simulating elements B mounted along the length of the post P. As will be clear from Figure 1, the branch-simulating elements B are adapted to receive a plurality of Christmas cards C.

More particularly, the post P may be formed of wood or plastic and conveniently is of square cross-section. As shown in Figure 3, the post P is formed at its opposite sides with a plurality of longitudinally spaced bores, the bores on the left side of the post being designated 10 and those on the right side being designated 11. The base F includes a rear foot 12 and a forwardly extending front foot 13. These members are of generally triangular configuration with their lower edge adapted to rest upon a floor or other horizontal supporting surface. The preferred embodiment of holder is adapted to have its rear

2

surface abut a vertically extending surface, such as a wall or the like. Accordingly, only three foot elements are disclosed. If it is desired to employ the holder at a distance spaced from a wall an additional foot element 5 may be provided. Alternately, three generally equidistantly spaced foot elements can be employed. Preferably, the foot elements 12 and 13 will be readily securable to and removable from the lower end of the post P. Thus, as shown in Figures 1 and 2, the rear foot 12 is detachably affixed to the post P by a bolt and nut combination 14, while the front foot 13 is detachably affixed to the post by a second bolt and nut combination 15 vertically spaced from bolt and nut combination 14.

The branch-simulating elements B are preferably formed of resilient steel wire. In Figure 2 one of these branch-simulating elements B is shown in its relaxed condition. It will be observed that at this time this element B is disposed entirely in a horizontal plane with its first and second ends 19 and 20 in close proximity. In assembling the holder the two ends 19 and 20 of the branch-simulating elements B are moved apart vertically and inserted within the bores 10 and 11, respectively, of the post P. Inasmuch as such flexing apart of the ends 19 and 20 will place the branch-simulating elements B in tension, these elements will remain in place upon the post P. Preferably, in the interest of realism, the branch elements B will increase in length from the upper portion of the holder to the lower so as to provide an upwardly tapered overall configuration. Thereafter, the Christmas cards C may be affixed along the length of each of the branch-simulating elements B, as by tape 22 or the like.

When the holder is to be disassembled, the wire ends 19 and 20 are removed from the bores 10 and 11. Additionally, it may be desirable to remove the foot elements 12 and 13 from the lower portion of the post P by unscrewing the bolt and nut combinations 14 and 15.

While there has been shown and described hereinbefore what is presently considered to be the preferred embodiment of the present invention it will be apparent that various modifications and changes may be made without departing from the spirit of the invention or the scope of the following claims.

I claim:

1. A tree-simulating Christmas card holder, comprising: a vertically extending, trunk-simulating post, said post being formed with a plurality of vertically spaced bores along its length; and a plurality of card-receiving, branch-simulating, elongated elements formed of resilient material, each of said elements assuming a substantially uniplanar position when in a relaxed condition, the ends of each of said elements being flexed vertically apart and removably inserted within a pair of vertically spaced bores of said post whereby said elements are placed in tension and will remain in place upon said post.

2. A tree-simulating Christmas card holder as set forth in claim 1 wherein the length of said branch-simulating elements increases from the upper portion of said post to the lower portion thereof so as to provide said holder with a downwardly tapered configuration.
